UNITED STATES PATENT OFFICE

ABRAHAM VANDER HENST, OF GRAND RAPIDS, MICHIGAN, ASSIGNOR TO W. B. JARVIS COMPANY, OF GRAND RAPIDS, MICHIGAN

CLOSURE FOR RADIATORS, TANKS AND THE LIKE

Application filed April 6, 1932. Serial No. 603,474.

The main objects of this invention are:

First, to provide a cap for radiators and the like having ornamental or aligning features with means for correctly adjusting the attaching mechanism of the cap relative to the body or aligning features to properly position the latter.

Second, to provide a closure for radiators and the like, which may be quickly removed and applied, the opening being effectively sealed and the closure being compact and projecting but slightly above the neck to which it is applied.

Objects relating to details and economies of my invention will appear from the description to follow. The invention is defined and pointed out in the claims.

A structure which is a preferred embodiment of my invention is illustrated in the accompanying drawing, in which:

Fig. 1 is a side elevation of a radiator cap embodying my invention.

Fig. 2 is a top plan view.

Fig. 3 is a bottom plan view, a portion of the ornament being broken off.

Fig. 4 is an enlarged fragmentary section taken on a line corresponding to line 4-4 of Fig. 3.

Fig. 5 is a top plan view of the neck.

Fig. 6 is a fragmentary section taken on line 6-6 of Fig. 5, showing the locking member.

Fig. 7 is a bottom view of the locking member in correct alignment, and

Fig. 8 is a view similar to Fig. 7 of the locking member before alignment.

Referring to the drawing, numeral 1 indicates the filler neck of an automobile radiator having an inturned flange 2 at its upper end providing an annular convex gasket seat.

On the inner edge of the flange 2 are provided opposed segmental cammed keepers 3 having diametrically opposed stops 4 at their ends.

The closure or cap 5 comprises an ornamental body member 6 having a depending peripheral flange 7 coacting with the shell 8 of the radiator (not shown). The body member 6 is provided with an integral centrally positioned depending stud or boss 9 having an integral lug 10 and an adjustable

lug 11 disposed in the opening 12. The adjustable lug 11 is provided with an eccentric head 13 having a transverse slot 14 therein for turning the adjustable lug with a screwdriver or like tool.

The resilient sheet metal closure disk 15 is provided with openings 16 receiving stationary lug 10 and the adjustable lug 11. A gasket 17 is interposed between the closure disk 15 and the end of the stud 9. The closure disk is preferably crowned somewhat and is preferably provided at its outer edge with a downturned flange 18 embracing the neck 1 and centering the closure thereon. A gasket 19 is arranged within the flange 16 to 60 coat with the seat formed on the top of the neck 1 by the inturned flange 2.

The stud 9 also carries a latch plate or locking member 20 which is provided with an opening 21 receiving the stationary stud 10 and a slot 22 for receiving the eccentric head 13 of the adjustable lug 11. The latch plate 20 and the closure disk 15 are secured to the stud 9 by the screw 23 which clamps the spring washer 24 into engagement with the 65 latch plate.

The latch plate is provided with opposed resilient locking or keeper engaging fingers 25 for coaction with the cammed keepers of the radiator neck 1. The comparative resilience between the closure disk and the locking fingers is preferably such that the disk is weaker or more resilient so that when the two are subjected to the same bending force the disk will be the first to yield unless prevented or stopped by the integral stops 26 depending from the body member 6, which are disposed above and near the rim of the closure disk 15, as illustrated by Fig. 4.

A shim 27 of copper or the like is disposed between the gasket and the closure disk 15 adjacent the depending flange 18 and in vertical alignment with the gasket. The shim 27 reduces the friction between the gasket and the closure disk, whereby the two are relatively rotatable and are not subject to the binding action which usually results in the distortion or mutilation of the gasket.

The latch plate 20 is adjusted on the depending stud 9 by loosening the screw 23 and 100

turning the adjustable lug 11 to the right or left, depending upon the direction of the adjustment. The eccentric head 13 of the adjustable lug 11 works in the slot 22 of the latch plate to swing it around the stationary lug 10. Fig. 7 shows the latch plate correctly adjusted for correctly aligning the forwardly projecting ornament 28 of the radiator cap. Fig. 8 shows the latch plate adjusted so that the ornament is inclined to the left. Dotted lines 29 and 30 of Fig. 2 indicate the approximate range of adjustment of the device. In prior devices, it has been rather difficult to assemble the radiator cap so that the ornament 28 assumes its correct position when the cap is positioned on the radiator neck. With my improved device, this adjustment may be quickly and accurately made by merely turning the adjustable lug 12, as pointed out above. After the correct adjustment has been made, the screw 23 is tightened so as to clamp the latch plate 20 and the adjustable lug 11 in their adjusted positions. The spring lock washer 24 is adapted to engage the eccentric head 13 of the adjustable lug 11 to hold the latter in place when the screw 23 is tightened.

It is obvious that various changes and modifications may be made in the details of construction and design of the above specifically described embodiments of my invention without departing from the spirit thereof, such changes and modifications being restricted only by the scope of the following claims.

Having thus described my invention, what I claim as new and desire to secure by Letters Patent, is:

1. The combination with the neck of a radiator or the like provided with keepers, of a closure comprising a body member having a depending stud provided with a threaded opening and with a lug at one side thereof and an adjusting lug having an eccentric projecting portion at the other side thereof, a closure member disposed on said stud to engage said lugs, a keeper engaging member having keeper engaging fingers and provided with holes engaging said lugs whereby said adjustable lug may be adjusted to position said keeper engaging member relative to said body member, and a screw threaded into said stud for securing the keeper engaging member in its adjusted position and in supporting engagement with said closure.

2. The combination with the neck of a radiator or the like provided with keepers, of a closure comprising a body member having a depending stud provided with a lug and an adjusting lug having an eccentric projecting portion, a closure member disposed on said stud to engage said lugs, and a keeper engaging member having keeper engaging fingers and provided with holes engaging said lugs whereby said adjustable member may be ad-

justed to position said keeper engaging member relative to said body member.

3. The combination with the neck of a radiator or the like provided with keepers, of a closure comprising a body member provided with a lug and with an adjusting member having an eccentric projecting portion, a closure member engaging said lug, and a keeper engaging member having keeper engaging fingers and provided with holes engaging said lugs whereby said adjustable lug may be adjusted to vary the position of said keeper engaging member relative to said body member.

4. A closure, having an internal depending stud provided with a threaded central opening, an integral lug on one side of said opening and an adjustable lug having an eccentric head on the other side of said opening, a keeper engaging member having radial arms and openings receiving said lugs, and a screw threaded to said stud in said central opening for securing said adjustable lug and said keeper engaging member in adjusted position.

5. A closure, having an internal depending stud, a fixed lug and an adjustable lug having an eccentric head on said stud, a latch member having radial arms and openings receiving said lugs, and a screw threaded to said stud for securing said adjustable lug and said member in adjusted position.

6. A closure, having an internal depending stud, a fixed lug and an adjustable lug having an eccentric head on said stud, a latch member having openings receiving said lugs, and a screw threaded to said stud for securing said adjustable lug and said member in adjusted position.

7. A closure, having an integral lug and an adjustable lug having an eccentric head, a latch member having openings receiving said lugs, and means for securing said adjustable lug and said member in adjusted position.

8. The combination with the neck of a radiator or the like provided with keepers, of a closure provided with an external projecting portion, a keeper-engaging member rotatably mounted within said closure so that it may be adjusted to position the projecting portion of the closure relative to the neck, eccentric means associated with said closure and member for rotatably adjusting said member and means for securing said keeper-engaging member in its adjusted position.

9. A closure having an internal depending stud provided with a lug, a latch member rotatably engaged with said lug, a second lug on said stud adjustable to position said latch member, and means for securing the latch member in its adjusted positions.

In witness whereof I have hereunto set my hand.

ABRAHAM VANDER HENST.
